DREDGING DEVICE

Carl W. Holland, Seattle, Wash.

Application December 4, 1944, Serial No. 566,586

5 Claims. (Cl. 37—189)

1

This invention relates to dredging devices, and has more particular reference to an improved dredging device of the type shown in the U. S. patent to Emil C. Wagner, No. 1,822,181, dated September 8, 1931.

The primary object of the present invention is to provide a dredging device of the above kind in which the suspension cable for the device is used to directly rotate the buckets so that sprocket or like gearings between the buckets and a shaft rotated by the cable are eliminated.

A further object of the present invention is to provide brakes adapted to automatically grip the cable and retain the receiver in receiving or dumping position when slack is provided in the cable by the device striking the bed of the river, or the like.

A further object of the invention is to generally improve and simplify the construction of dredging devices of the above kind.

The present invention consists in the novel form, combination and arrangement of parts hereinafter more fully described, shown in the accompanying drawings and claimed.

In the drawings, wherein like reference characters indicate corresponding parts throughout the several views:

Figure 1 is a side elevational view, partly broken away and in section, of a dredging device constructed in accordance with the present invention.

Figure 2 is a substantially central vertical section taken on line 2—2 of Figure 1.

Figure 3 is a fragmentary vertical transverse section taken on line 3—3 of Figure 2.

Figure 4 is a fragmentary view showing one of the brakes in applied position.

Figure 5 is a diagrammatic view showing the cable, guides and pulleys, and illustrating the manner in which the device is operated.

Referring in detail to the drawings, the present dredging device includes a cylindrical receiver 5 having an opening 6 in its peripheral wall. The receiver 5 has an axial horizontal shaft 7 whose projecting ends are journaled in the legs of an inverted U-shaped frame 8. Discs 9 are frictionally rotatably mounted on the shaft 7 between the ends of the receiver 5 and the legs of frame 8, and these discs carry a circular series of buckets 10 arranged near and rotatable about the receiver 5. Pulleys 11 are fixed to the outer sides of the discs 9, and guide pulleys 12 are mounted on and disposed at the inner sides of the legs of frame 8 above the pulleys 11 and buckets 10. Further guide pulleys 13 are journaled in open-

2

ings provided in the intermediate portion of frame 8 inwardly of the pulleys 12, and the pulleys 12 are of the double type. A cable 14 extends from a distant winding drum 15, as shown in Figure 5, and around a guide pulley 16, then under one pulley 13, laterally to the adjacent side of frame 8 and over a pulley 12, then downwardly and around the pulley 11 at the adjacent side of the frame, then upwardly over the mentioned pulley 12, then to the opposite side of the frame 8 and over the other pulley 12, then downwardly and around the other pulley 11, then upwardly over the second-named pulley 12, then under the other pulley 13 and over another guide pulley 16a to a second winding drum 15a. The guide pulleys 16 and 16a may be carried by the boom of the dredge, and it will thus be seen that the cable 14 serves both as a suspension cable for the dredging device and a driving cable for the buckets. As the cable 14 passes around the pulleys 11, the buckets are directly driven thereby so as to eliminate any sprocket gearings between the buckets and a counter shaft driven by the suspension cable.

Stop members 17 are secured to the outer sides of the legs of frame 8 above and below the shaft 7 and to one side of the axis of the latter. Fixed to and rotatable with the shaft 7 are arms 18 respectively engageable with the stop members 17 that are located above the shaft 7 when the receiver is in receiving position with its opening 6 at the top, as shown in Figure 1, and with the stop members 17 which are below the shaft 7 when the receiver is disposed in dumping position with its opening 6 at the bottom, as shown in Figure 3.

The arrangement is such that when the cable is wound on the drum 15a and simultaneously unwound from drum 15, the pulleys 11 will be driven in a direction to cause counterclockwise rotation of the buckets, as viewed in Figures 1 and 3. When this takes place, the receiver is rotated to the receiving position of Figure 1 due to the frictional engagement of discs 9 and pulleys 11 with shaft 7, the receiver being stopped in such receiving position by engagement of the arms 18 with the upper stops 17. Upon continued rotation of the buckets, they will scoop the material at the bottom of the device and will dump the scooped material into the receiver through its opening 6 at the top of the device. Dumping of the receiver is effected by rotating the buckets in a clockwise direction, as viewed in Figures 1 and 3, at which time the cable 14 is wound on drum 15 and unwound from drum 15a, thereby reversing

the direction of travel of the cable. Due to the frictional engagement between the discs 9 and pulleys 11 with shaft 7, this rotation of the buckets will be transmitted to the receiver until the latter moves from the receiving position of Figure 1 to the dumping position of Figure 3. In the dumping position, the opening 6 is located at the bottom of the device and the material freely flows by gravity from the receiver 5 through the opening 6 of the receiver.

A pair of spring-applied, substantially C-shaped brakes 19 are pivoted in the frame 8 outwardly of the pulleys 13, and disposed between the upper arms of these brakes is a block 20 carried by the frame 8. The runs of the cable 14 pass between opposite sides of the block 20 and the upper arms of the brakes 19, and the lower arms of said brakes carry rollers 21 which bear upon the cable 14 at points between the rollers 12 and 13. The arrangement is such that when the cable 14 is placed in a taut condition, it will rock the brakes 19 against the action of their actuating springs 22 so as to release the upper arms of the brakes 19 from the cable. On the other hand, when slack is presented in the cable 14, the springs 22 will rock the brakes 19 in a direction to cause their upper ends to bind the cable 14 against opposite sides of the block 20 and retain the cable in engagement with the pulleys 11. Thus, movement of the cable and rotation of the buckets and receiver is prevented when slack is provided in the cable, thereby insuring retention of the receiver in receiving or dumping position until such slack is removed from the cable. This is desirable when the slack is caused by the dredging device striking the bed of the river or the like. It will be noted that as soon as the winding of cable 14 begins, the slack is removed from the cable and the brakes are released so as to permit driving of the buckets.

From the foregoing description, it is believed that the construction and operation, as well as the advantages of the present invention, will be readily understood and appreciated by those skilled in the art. Minor changes may be made in details of construction illustrated and described, such as fairly fall within the spirit and scope of the invention as claimed.

What I claim is:

1. A dredging device comprising a cylindrical receiver having a horizontal axial shaft provided with projecting ends, a frame in which the ends of said shaft are journaled, said receiver further having an opening in its periphery, discs provided with pulleys and rotatable on but having frictional engagement with the shaft, buckets carried by said discs and revoluble about and substantially in contact with the periphery of the receiver, means to suspend the device and revolve the buckets in either direction including a single cable passing around said pulleys, and stop means limiting rotary movement of the receiver to positions wherein the opening is uppermost and lowermost, respectively.

2. A dredging device comprising a cylindrical receiver having an opening in its periphery, a bucket unit including rigidly connected buckets revoluble about and substantially in contact with the periphery of the receiver, pulleys fixed to the ends of the bucket unit and operable to revolve the latter, said pulleys being coaxial with the receiver and the bucket unit, said buckets

being open at the side next to the receiver, a support for the receiver permitting its free oscillation about its axis, suspension means for the device including a single cable passing about said pulleys for revolving the buckets in either direction and by frictional engagement tending to rotate the receiver in like directions, and stop means limiting rotary movement of the receiver to positions wherein the opening is uppermost and lowermost, respectively.

3. A dredging device comprising a cylindrical receiver having an opening in its periphery, buckets revoluble about and substantially in contact with the periphery of the receiver, pulleys connected to the buckets and operable to revolve the latter, said buckets being open at the side next to the receiver, a support for the receiver permitting its free oscillation about its axis, suspension means for the device including a cable passing about said pulleys for revolving the buckets in either direction and by frictional engagement tending to rotate the receiver in like directions, stop means limiting rotary movement of the receiver to positions wherein the opening is uppermost and lowermost, respectively, and spring-applied brakes for preventing the provision of undue slack in those portions of the cable passing around the pulleys when the cable is provided with slack directly above said support, said brakes being associated with said cable so as to be released by the latter when said cable is placed in a taut condition.

4. A dredging device comprising a cylindrical receiver having an opening in its periphery and provided with a horizontal axial shaft, a frame in which said shaft is journaled, discs provided with pulleys and rotatable on and having frictional engagement with said shaft, buckets carried by said discs and revoluble about and substantially in contact with the periphery of the receiver, said buckets being open at the side next to the receiver, a suspension cable for the device passing around said pulleys for revolving the buckets in either direction and by the frictional engagement of the discs with the shaft tending to rotate the receiver in like directions, and stop means limiting rotary movement of the receiver to positions wherein the opening is uppermost and lowermost, respectively.

5. A dredging device comprising a cylindrical receiver having an opening in its periphery and provided with a horizontal axial shaft, a frame in which said shaft is journaled, discs provided with pulleys and rotatable on and having frictional engagement with said shaft, buckets carried by said discs and revoluble about and substantially in contact with the periphery of the receiver, said buckets being open at the side next to the receiver, a suspension cable for the device passing around said pulleys for revolving the buckets in either direction and by the frictional engagement of the discs with the shaft tending to rotate the receiver in like directions, and stop means limiting rotary movement of the receiver to positions wherein the opening is uppermost and lowermost, respectively, said stop means including stop members fixed to the frame above and below the shaft and arms carried by and rotatable with the shaft and alternately engageable with the stop members above and below the shaft.

CARL W. HOLLAND.
